UNITED STATES PATENT OFFICE.

HARRY J. McMASTER, OF SEBRING, OHIO.

DRYING-RACK FOR POTTERY.

1,258,425.

Specification of Letters Patent.

Patented Mar. 5, 1918.

Application filed October 30, 1917. Serial No. 199,245.

To all whom it may concern:

Be it known that I, HARRY J. McMASTER, a citizen of the United States, residing at Sebring, in the county of Mahoning and State of Ohio, have invented a new and useful Drying-Rack for Pottery, of which the following is a specification.

This invention relates to drying racks for pottery and has for its object to provide a device of this character which will eliminate a great portion of the labor of handling the pottery between the different operations in its manufacture.

Another object is to provide a device of this character that will tend to reduce the loss in potteries due to the breakage incident upon necessary handling of the pottery by the present methods.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims without departing from the spirit or sacrificing any of the advantages of the invention.

30 In the accompanying drawings:

Figure 1 is a longitudinal sectional view of my device, showing one of the series of removable shelves in dotted lines in the position which it assumes while the pottery is being removed therefrom and new ware placed thereon.

Fig. 2 is a plan view of my device with the extreme upper end of the central shaft broken away.

40 Fig. 3 is a cross sectional view through the track and rolling hanger therein.

Fig. 4 is a side elevation of the hanger with fragmentary portions of the supporting beam, track and shelf carrying beam.

45 Fig. 5 is a detail perspective view of my latch member for holding two sections of track in alinement.

Similar numerals of reference indicate corresponding parts throughout the several 50 figures of the drawings.

In manufacturing pottery such as table-ware and the like it is well known to those skilled in the art that the ware having been turned out upon a jigger is placed upon a

rack or shelf by the jiggerman, is then conveyed by another workman, usually a boy, to shelves or racks where it is placed until it has become sufficiently dried to enable another workman to begin the next process in manufacture, known as "finishing", which 55 consists of removing the rough edges from the dried clay. The drying racks are usually located at a distance of fifteen to thirty feet from the jigger, and about an equal distance from the finisher's machine, which necessitates carrying the mold bearing the 60 newly formed soft clay ware from the jigger to the drying rack as above described, and then when sufficiently dried to permit of handling without danger of misshaping the 65 ware, to the finisher. By this method considerable time is lost in simply carrying the ware from one step in the process to another and considerable loss due to breakage results from such handling of the ware. 70

75 My device is designed to eliminate the necessity for the workman, who is now employed to simply carry the pottery between the drying racks and the above mentioned steps in the manufacture.

80 Referring particularly to Fig. 2 of the drawings the jiggerman or workman who first forms the ware in soft clay upon a mold stands approximately at the position indicated by "A", facing in the direction indicated by the arrow, his jigger machine of course being located immediately in front of him. The finisher or workman who removes the rough edges from the ware after it has become sufficiently dried stands ap-

85 proximately at the point indicated by "B", also facing in the direction of the arrow and of course with his machine located immediately in front of him. My drying rack is therefore arranged in the most convenient 90

95 manner for both workmen and is constructed as follows: a central vertical shaft 1 resting upon a ball bearing base 2 is arranged centrally of the drying room. Near the upper extremity of the shaft 1 is an annular collar 3 with a laterally extending flange and spaced a short distance below the collar 3 is a substantially similar collar 4. A series 100 of holes adapted to receive bolts 5 are formed in the laterally extending flange of the collar 4 and a series of horizontal beams 6 having holes, adapted to register with the holes in the flange of the collar 4, adjacent one

end thereof are placed upon the said flange and secured thereto by means of the bolts 5. A series of holes is also formed in the flange of the collar 3, the said holes being adapted 5 to receive one end of tie-rods 7 which extend downwardly and outwardly and are secured at their opposite ends to the beams 6. Turn-buckles 8 are placed intermediate the ends of the tie-rods for a purpose hereinafter to be set forth. Depending from the beam 6 and bolted thereto are clips 9 clearly shown in Figs. 3 and 4, which are adapted to support tubular track sections 10 arranged below the beams 6. As shown in Fig. 2, I 10 connect the beams 6 by means of lateral members 11 which are located at a point near the inner extremities of said beams. A series of similar supports 12 are located near the outer extremities of said beams and 15 intermediate the ends of each section of said supports 11 and 12 I secure a beam 14 similar to the beams 6, except that they are shorter than said beams 6 and beneath the said beams 14 I support tubular track sections 10 identical, except in length, with the sections supported beneath the beams 6. Tie-rods with turn-buckles therein identical with the tie-rods supporting beams 6 are attached to the beams 14 and collar 3.

20 Located within each of the track sections is a pair of truck members 15, the said truck members having bifurcated ends 16 in which are located rollers 17, which are adapted to operate within the said track. A slot 18 25 as clearly shown in Fig. 3 is formed longitudinally of each track section for its entire length and the upper section 19 of a hanger is secured to the said truck members and extends downwardly through the slot 18. The lower section 20 of the said hanger is hingedly secured to the section 19 as shown and is adapted to straddle a beam 21 to which it is bolted. Secured to either end of the beams 21 and extending downwardly therefrom are planks 22, which form end supports for a series of shelves 23.

30 The whole of the above described structure is adapted to be placed within a room, the walls of which are indicated at "C" and 35 in the front wall is located an opening "D" for a purpose to be hereinafter pointed out. Secured to the ceiling just outside the room above mentioned and adjacent the wall with the opening D therein are downwardly extending members 24, to the lower ends of which are secured a beam 25 substantially similar to the beams 6 and secured thereunder by means of clips 26 is a tubular track section 27 identical with the track sections 40 45 50 55 60 65 70 75 80 85 90 95 100 105 110 115 120 that the frame has made one complete revolution, bringing the first filled section back to register with the opening D, the ware which had been placed upon it has become 5 sufficiently dried for the finisher to remove it from the molds for the finishing process, the section again being rolled out through the opening D on to the track 27 where the ware is removed from the molds by the finisher, 10 the empty mold being left upon the shelf to have a fresh piece of ware placed upon it by the jiggerman. It is obvious by this method that the workmen previously necessary to carry the ware back and forth is 15 eliminated, much time therefore being saved and since the ware requires about fifty percent less handling, a great deal of breakage due to such handling is also eliminated.

Having fully described my invention, 20 what I claim as new and desire to secure by Letters Patent, is:—

1. In a drying rack for pottery of the character described, a vertical shaft, a plurality of radially disposed arms supported 25 upon said shaft, tubular track sections secured beneath said radial arms, rollers adapted to move within said track sections, supporting hangers depending from said rollers and adapted to carry sections containing a series of horizontally disposed shelves, a single track section located at a 30 point adjacent said radial arms and means for temporarily locking the said radial arms in alinement with the said single track section.

2. In a drying rack for pottery of the character described, a vertical shaft, radially disposed arms supported upon said shaft and extended therefrom, tubular track sections secured beneath said radial arms, a single track section located adjacent said radial arms, each of said track sections beneath said radial arms being adapted to be moved into alinement with said single track 40 section and means for insuring accurate vertical alinement between said single track section and track sections supported beneath said vertical arms.

3. In a drying rack for pottery of the character described, a vertical shaft, radially disposed arms supported upon said shaft and extended therefrom, tubular track sections secured beneath said radial arms, a single track section located adjacent said radial arms, each of said track sections beneath said radial arms being adapted to be moved into alinement with said single track section and means for temporarily locking each of said track sections supported beneath 50 the radial arms in alinement with said single track section.

4. In a drying rack for pottery of the character described, a vertical shaft adapted to rotate upon a ball bearing base, a plurality of radially disposed arms supported

upon said shaft and extending therefrom, a tubular track section supported beneath each of said radial arms, a series of horizontally disposed shelves hingedly connected to roller carrying members, said rollers 70 being adapted to operate upon the inner surface of said tubular track, the said tubular tracks each being adapted to be brought into alinement with a single tubular track, the said rollers moving from the track sections 75 beneath said radial arms to the single track section alined therewith, thereby carrying the said series of shelves depended therefrom to a position beneath said single track section. 80

5. In a pottery drying rack of the character described, a vertical shaft adapted to be rotated upon a ball bearing base, a collar secured to said shaft intermediate its ends, a series of arm members bolted to said collar and extending radially from said shaft, a series of supports connecting said arm members and a second series of radial arms secured to said supports at a point intermediate the first series of said radial arms, each 90 of both series of said radial arms having suspended thereunder a tubular track section, a single tubular track section arranged radially to said shaft and spaced therefrom the length of one of said first mentioned 95 series of radial arms, the track section beneath each of said radial arms being adapted to be moved into alinement with said single track section and means for temporarily locking the track sections in such 100 alinement.

6. In a pottery drying rack of the character described, a vertical shaft adapted to be rotated upon a ball bearing base, a collar secured to said shaft intermediate its ends, 105 a series of arm members bolted to said collar and extending radially from said shaft, a series of supports connecting said arm members and a second series of radial arms secured to said supports at a point intermediate the first series of said radial arms, each of both series of said radial arms having suspended thereunder a tubular track section, a single tubular track section disposed radially to said shaft and spaced 110 therefrom the length of one of said first mentioned series of radial arms, the track section beneath each of said radial arms being adapted to be moved into alinement with said single track section, a second collar secured to said shaft at a point above 115 the first mentioned collar, tie-rods secured at one end to each of said radial arms and at the other end to the second mentioned collar, adjusting means upon each of said tie-rods for insuring perfect vertical alinement 120

125 between the track sections beneath said radial arms and the said single track section.

7. In a drying rack for pottery of the character described, a vertical shaft, a plu- 130

rality of radially disposed arms supported upon said shaft, track sections beneath said radial arms, a truck provided with rollers adapted to move upon said track sections, supporting hangers adapted to carry a series of horizontally disposed shelves, a single track section located at a point adjacent

the sweep of the outer ends of the radial arms and means for temporarily locking said radial arms in alinement with said single track section. 10

In testimony that I claim the above, I have hereunto subscribed my name.

HARRY J. McMASTER.
